ABSTRACT

A spray nozzle characterized by a body portion on which one end of a shank is pivotally mounted for swinging movement toward and away from a position in which a resilient member carried by an arm depending from the shank is in sealing engagement with one face of an egress port comprising the two faces of a dihedral angle intersected by a flow passage extending through the body. When the shank is swung away from the position stated, both faces of the dihedral angle are exposed, thereby permitting the flushing from the egress port of any material which may be clogging it when said one of the angle faces is engaged with and sealed off by the resilient member.

FIG. 7

FLUSHABLE NOZZLE HAVING MEANS FOR REDIRECTING AND DISPERSING THE EFFLUENT

BACKGROUND AND SUMMARY OF THE INVENTION

The present invention relates to spray nozzles in the operation of which a flowing stream of liquid is redirected and dispersed by some surface means positioned beyond the egress port or point of last confinement of the liquid and in a direct line therewith to accomplish a change in the direction of flow of the liquid. Such means is usually called a deflector by which there is meant a solid means arranged exteriorly of the egress port to redirect and disperse the effluent and change its characteristics, as from a solid stream substantially circular in cross section to a flattened or fan-shaped spray discharge or curtain.

An important application for spray nozzles of the above-described type is in the field of effective foam control in sewage treatment plants, where a battery of such nozzles is arranged to spray and beat down the foam that is formed and rises as the result of the reaction of sewage with the chemicals used to treat the sewage. A nozzle designed for this purpose is disclosed in the Hanson U.S. Pat. No. 3,066,870, granted Dec. 4, 1962, and another is disclosed in the Ross U.S. Pat. No. 3,257,079, granted June 21, 1966. In both these nozzles the egress port for the liquid lies in one plane with no portion being closed off, and the discharge impinges head on with a closely adjacent flat deflector surface parallel with the plane of the egress port and arranged at 90° to the axis of discharge, thereby causing an abrupt and sharp change of direction of the discharge and a maximum splashing in all directions which requires the use of an arcuate rib or wall to control and direct the discharge downwardly toward the sewage. The spacing between the egress port and the deflector surface is narrow, with the result that there is frequent clogging of the egress port by particles in the effluent, and to clear the port the deflector surface is so mounted as to be manually swingable up and out of the way of the port, thereby permitting the force of the discharge to clear and flush away the cause of clogging.

The present invention also relates to spray nozzles for use in foam control in sewage treatment plants and has as its object improvement over the nozzles disclosed in the above Hanson and Ross patents. To this end the present invention contemplates that the egress port be the two faces of a forwardly directed dihedral angle intersected by the passage through which the liquid to be sprayed flows, and the present invention further contemplates that one of these faces be sealed off during the spraying operation by one portion of a deflector surface another portion of which functions to redirect downwardly gradually and not abruptly the discharge from the opening or egress port portion formed by the other dihedral angle face. The present invention further contemplates that should clogging occur in this other or open egress port portion, the deflector may be manually swung up and away from the egress port as a whole, thereby exposing both faces of the dihedral angle, i.e., the entire egress port, so that it may be cleared of clogging by the flushing action of the liquid discharge. The present invention also contemplates that while the deflector element, like that in the Hanson and Ross patents, is made of some resilient material, it is

mechanically locked in place in its mounting without relying for this purpose upon what is only a frictional fit which can loosen or upon some metallic fastening means which can become corroded.

5 To achieve the above-contemplated ends the various features of the present invention reside in certain constructions, combinations, and arrangements of parts which are all fully described in the following detailed description of the preferred embodiment and are then 10 set forth in the appended claims by the intentional use of generic terms and expressions that are inclusive in meaning of various modifications.

BRIEF DESCRIPTION OF THE SEVERAL VIEWS OF THE DRAWING

15 FIG. 1 is a view in plan of a preferred embodiment of the present invention;

20 FIG. 2 is a detail view in side elevation, partially in section, of the embodiment shown in FIG. 1;

25 FIG. 3 is a detail view in full sectional elevation, with the pin in full line, taken as along the line 3—3 of FIG. 2;

30 FIG. 4 is a view in front elevation with the shank, arm, and deflector in raised position to expose the egress port fully;

35 FIG. 5 is a view in side elevation of the resilient member;

40 FIG. 6 is a detail view in side elevation, partially in section, corresponding to FIG. 2 but showing the axis of the through passage above the dihedral angle edge; and

45 FIG. 7 is a detail view similar to FIG. 6 but showing the axis of the through passage below the dihedral angle edge.

DETAILED DESCRIPTION OF THE PREFERRED EMBODIMENT

Referring to the drawing, the illustrated embodiment of the present invention is provided with a nozzle body 10 having a rear or inlet portion 11, shown as externally threaded for connection to a source of liquid under pressure, and a forward or discharge portion 12 the front of which consists of the upper face 13 and the lower face 14 of a forwardly directed dihedral angle. 50 The body 10 is also provided with a through passage 15 extending from the inlet portion 11 through the dihedral angle 13-14, thereby intersecting it to form an egress port 16, and the body 10 is completed by a pair of spaced upstanding ears 17 provided with aligned 55 passages 18.

The ears 17 receive loosely between them the rear end of a shank member 19 provided with a passage 20 of appreciably greater diameter than and alignable with the ear passages 18 so that a cylindrical pivot pin 21 60 may be received by the passages 18 and 20 to permit swinging of the shank member 19. The forward or free end of the shank member may be provided with a solid enlargement 22 which functions as a weight to increase the effective pressure or load exerted by the shank 19 when in forward position, as will be described.

As best shown in FIG. 4, the dihedral angle edge 23 and the axis of the pin 21 are parallel. The pin 21 may have knurling 24 (FIG. 3) at one end portion to insure a snug fit in an ear passage 18, but by reason of the loose fit of the rear end of the shank member 19 between the ears 17 and by reason of the fact that the shank passage 20 has a diameter greater than that of

the ear passages 18, and therefore of the pin 21, the shank 19 is capable of a slight lateral rocking movement in addition to pivotal movement on the pin 21 for a purpose which will be described.

Shown as integrally formed on the rear portion of the shank member 19 but ahead of its pivoting on the pin 21 is a boss 25 extending outwardly from each side of the shank 19, and therebeneath the boss 25 is provided with a downwardly and forwardly extending integral arm 26 which is dependent from the boss 25 in such position that an area of the arm is locatable in front of the dihedral angle 13-14 when the shank 19 is substantially horizontal, as shown in FIG. 2, this occurring because the arm 26 is stationary relatively to the shank 19 and is swingable therewith and thereby.

The arm 26 is appreciably wider than the forward discharge portion 12 of the body 10 on which the dihedral angle 13-14 is formed, and located rearwardly in the lower portion of the arm 26 (viewing FIG. 2) is a socket 27 from the base of which a through passage 28 of reduced diameter extends to the front face of the arm 26. The socket is shown as circular (FIG. 4) and is adapted to receive as an insert a resilient, i.e., rubber or rubber-like, member indicated generally at 29 in FIG. 5, which consists of a disc-like portion 30 from the top of which a shank 31 of reduced diameter extends, surmounted by an enlarged, tapered end portion 32 forming an annular shoulder 33 with the shank 31.

Because the member 29 is of resilient material it may be readily forced into the socket 27 so that the disc-like portion 30 is seated therein and so that the shank 31 is located in the passage 28 with the tapered end portion 32 extending beyond the arm 26 and with the shoulder 33 engaging the front face of the arm 26. To facilitate introducing the disc-like portion 30 into the socket 27 the former may be provided with a chamfer 34 and to facilitate introducing the tapered end portion 32 into the passage 28 the latter may have a chamfer 35 at its base, but it should be noted that by reason of the engagement of the shoulder 33 with the arm 26 (FIG. 2) the resilient deflector 29 is mechanically locked in place on the arm 26 against displacement during use, and as the result of use, of the nozzle construction as is described infra. As a result the fit of the disc-like portion 30 in the socket 27 need not be a frictionally snug fit such as would be intended to hold the portion 30 in the socket 27 by such friction alone, and there is eliminated use of a metallic fastening which could become corroded.

With particular reference to FIGS. 2 and 4, it will be noted that the lower portion of the arm 26 is cut away on its rear face thereby providing a shoulder 36 and that the central portion of this shoulder is intersected (FIG. 4) by the upper portion of the socket 27. This upper portion thus constitutes an arcuate wall surface 37 which it will be noted is of greater depth than the thickness of the adjacent portion of the seated resilient member 29, this wall surface being directed downwardly toward the discharge portion 12 and extending rearwardly from the plane of the upper dihedral angle face 13 when the resilient member 29 is engaged with said face.

The functions of the resilient member 29 are twofold: (1) to seal off that portion of the egress port 16 bounded by the upper dihedral angle face 13, and (2) to form a deflector for redirecting and dispersing into

a fan-shaped spray the discharge of liquid flowing to the egress port 16 through the body passage 15.

For the first of these functions the location of the arm 26 on the shank 19 is such that when the shank is swung to its forward position in use (FIG. 2) during spraying, the resilient member 29 is engaged with the body discharge portion 12, and the angularity of the arm 26 with respect to the shank 19 is such that also when the shank is swung to its forward position during spraying 10 the resilient member 29 engages the dihedral angle face 13 flatwise to seal it off. The weight of the shank 19 including that of the enlargement 22 provides sufficient load to cause the resilient member to press against and be slightly depressed by the dihedral angle face 13 to 15 effect the sealing, and the fact that the pin 21 and passages 18 and 20 pivot construction above described permits a slight lateral rocking movement during swinging of the shank 19 about the axis of the pin 21 results in the resilient member 29 being self-seating, as it were, 20 to perfect the sealing action. It will be understood that for an intended pressure on the discharged liquid, i.e., 3-10 psi, the shank 19 and the enlargement 22 have sufficient weight to maintain the resilient member seated during the spraying operation.

25 For the second of the above two functions for the resilient member 29, it will be noted from FIG. 2 that with the portion of the egress port 16 bounded by the upper dihedral angle face 13 sealed off by the resilient member, liquid can be discharged through only that part of the egress port 16 bounded by the lower dihedral angle face 14, and that the portion of the deflector member 29 lying directly ahead of the lower angle face 14 and so in the path of the discharged liquid is downwardly and forwardly directed to terminate in a curved 30 lip 38 extending across the width of the disc-like portion 30. As a result, while there is a definite and intended redirection of the effluent liquid discharge by the resilient member 29, it is a gradual redirection in contrast to a sharply abrupt redirection such as results 35 from a flat deflector surface located at 90° to the axis of discharge flow as in the Hanson and Ross patents, and two important consequences of this gradual redirection in contrast to abrupt redirection are that there 40 is a minimum of side spread or splash of the effluent discharging liquid and the angle of the spray fan is sharply defined and regular.

45 As brought out above, during the spraying operation the shank 19 is in a forward position with the resilient member 29 in sealing engagement with the upper dihedral angle face 13 of the egress port 16 as shown in FIG. 2. Should the lower portion of the port 16, i.e., the portion thereof exposed at the dihedral angle face 14, become clogged with particles of foreign matter not properly strained from the liquid being sprayed, the shank 19 may be manually swung upwardly and rearwardly, as indicated in construction lines in FIG. 2, by reason of the pivotal mounting on the body 10 so that the arm 26 is out of the path of the discharge, with the result that the entire egress port 16 is exposed and the pressure of the liquid flowing through the body passage 15 causes a flushing action which clears away the obstructing matter. Thereupon the shank 19 is swung back to its forward position to seal off the upper dihedral angle face 13 so that redirection and dispersing of the effluent liquid is resumed.

50 The egress port and deflector surface constructions described above are designed to produce an efficient

flat spray pattern under low liquid pressure conditions, by which there is meant pressures in the order of 3-10 psi as opposed to much greater pressures. It has been found, however, in some sewage treatment plants in which embodiments of the present invention have already been installed that the operators there have not observed the low pressure feature and instead have had the liquid under as much as 40 psi pressure, a greatly excessive pressure which materially increases pumping costs and results in the spray itself churning the contents of the sewage tanks and so creating more foam in addition to the foam which embodiments of the present invention are designed to beat down.

This undesirable situation is, of course, corrected by the proper observance of operating instructions, but where the situation exists there may be a tendency for the excessive pressure to cause a partially upward or outward splashing of the discharged liquid during the initial stage of the upward swinging of the shank 19 to clear the egress port 16, this tendency being only momentary and ending as soon as the resilient member 29 is substantially out of the path of discharge from the egress port 16. Any such splashing is undesirable because it may cause liquid to strike the operator or may cause otherwise dry portions of the environment of the installation to become wet, and the arcuate wall surface 37 (FIG. 2) thus functions as an impingement surface to direct downwardly any splashing occurring during the initiation of the upward swing of the shank 19. As shown in FIG. 2, the wall surface 37 is inoperative for this purpose during spraying, i.e., when the resilient member 29 engages the port 16 to seal off the dihedral angle face 13, and functions during the initial phase of the upward swinging of the shank 19, being downwardly directed and extending rearwardly from the plane of the dihedral angle face 13 when the resilient member 29 engages that face to seal it off.

As a further feature of the present invention and with reference to FIG. 2, it will be noted that the axis A—A of the body passage 15 intersects the dihedral angle edge 23 so that the angle faces 13 and 14 are the same size, each being one half of the egress port 16. With a given liquid pressure the FIG. 2 construction would thus produce a fan-shaped spray having a given spray angle of spread which may be regarded as standard for that pressure.

If it be desired to cause the fan spray to have a smaller angle of spread, this result can be achieved by giving the lower angle face a smaller size than the upper, while retaining the parallelism of the dihedral angle edge with the axis of the pin 21, and this is shown in FIG. 6, the angle edge 23A being located below the axis A—A of the body passage 15 and the larger upper angle face 13A and the smaller lower angle face 14A corresponding to the respective faces 13 and 14 in FIG. 2. The angle faces 13A and 14A make up the egress port 16A which corresponds to the port 16, but the angle face 14A is less than one half of that port by reason of being smaller than the face 13A.

Conversely, the fan spray may be given a greater angle of spread than the standard angle noted above by causing the lower angle face to have a greater size than the upper, while retaining the parallelism of the angle edge with the axis of the pin 21. This is shown in FIG. 7, the dihedral angle edge 23B being located above the axis A—A of the body passage 15 and the smaller upper angle face 13B and the larger lower angle face

14B corresponding to the respective faces 13 and 14 in FIG. 2. The angle faces 13B and 14B make up the egress port 16B which corresponds to the egress port 16, but the angle face 14B is more than one half of that port by reason of being larger than the face 13B. In each of FIGS. 2, 6, and 7 the disc-like portion 30 of the resilient deflector member 29 engages and seals off the respective dihedral angle faces 13, 13A, and 13B so that liquid is discharged against the resilient member 29 through only the exposed port portions bounded by the angle faces 14, 14A and 14B, respectively.

What is claimed as new is:

1. In a spray nozzle characterized by having a body portion provided with a through passage, an egress port at one end of the through passage for the discharge of liquid, an elongated shank member extending forwardly of the body portion, said shank member being pivotally mounted at its rear end on the body portion for manual swinging movement about an axis, and a deflector for redirecting and dispersing the flow of discharged liquid, the improvement which comprises:

A. the egress port being formed by the intersection of said through passage with the two faces of a forwardly directed dihedral angle formed on said body portion;

B. an arm carried by the rear portion of the shank member adjacent to but forwardly of its pivotal mounting and depending from said shank member in stationary relation thereto and swingable therewith and thereby from a position in which an area of the arm is in the path of the discharged liquid to and from a position in which said arm area is out of the path of the discharge;

C. the arm being provided with a socket in said area and with a resilient member seated in said socket and engageable with one of the faces of the dihedral angle, when the arm area is in the path of the discharged liquid, to seal off the egress port portion bounded by said one of the faces whereby liquid is then discharged through only the port portion exposed at said other face, said resilient member providing at that time a surface for redirecting and dispersing the flow of liquid thus discharged; and

D. the greater part of the shank member being located forwardly of both the egress port and the arm, when the resilient member is engaged with a dihedral angle face, to provide a weight load causing the resilient member normally to be maintained seated on said face for an intended pressure on the discharged liquid.

2. Structure such as set forth in claim 1 characterized by the fact that the through passage has a central axis which intersects the edge of said dihedral angle.

3. Structure such as set forth in claim 1 characterized by the fact that the dihedral angle edge is so located that less than one half of the egress port is exposed when the resilient member is in said face-sealing and flow redirecting and dispersing position.

4. Structure such as set forth in claim 1 characterized by the fact that the dihedral angle edge is so located that more than one half of the egress port is exposed when the resilient member is in said face-sealing and flow redirecting and dispersing position.

5. Structure such as set forth in claim 1 characterized by the fact that the depth of a portion of the arm socket wall is greater than the thickness of the adjacent portion of the resilient member when seated, thereby pro-

viding a wall surface extending beyond the exposed surface of the resilient member, said wall surface being downwardly directed and extending rearwardly from the plane of the face of the dihedral angle engageable with the resilient member when the resilient member is so engaged.

6. Structure such as set forth in claim 1 characterized by the fact that the arm is provided with a passage extending therethrough from the base of the socket and the resilient member is provided with a shank received in said arm passage and having an enlarged portion engaged with the arm beyond the arm passage to lock the resilient member in place.

7. In a spray nozzle characterized by having a body portion provided with a through passage, an egress port at one end of the through passage for the discharge of liquid, and a deflector for redirecting and dispersing the flow of discharged liquid, the deflector being mounted for manual swinging movement about an axis from a position in which a surface of the deflector is in the path of the discharged liquid to redirect and disperse the same to and from a position in which said surface is out of the path of the discharged liquid, the improvement which comprises:

A. the egress port being formed by the intersection 25

of said through passage with the two faces of a forwardly directed dihedral angle formed on said body portion;

- B. a portion of the deflector surface which is located in the path of the liquid discharge when the deflector is in flow redirecting and dispersing position being engageable with one of said faces to seal off the egress port portion bounded thereby so that liquid is then discharged against the deflector through only the port portion exposed at said other face;
- C. the deflector being provided with a socket and with a resilient member seated in the socket, said portion of the deflector surface which is located in the path of liquid discharge as stated being a surface of said resilient member; and
- D. the depth of a portion of the socket wall being greater than the thickness of the adjacent portion of the resilient member when seated, thereby providing a wall surface extending beyond the exposed surface of said resilient member, said wall surface being downwardly directed and extending rearwardly from the plane of the face of the dihedral angle engageable with the resilient member when the resilient member is so engaged.
